of handles 16 and 17 at its opposite ends for manually transporting the same from place to place, as required.

The frame 15 is designed also to carry a suitable burner apparatus indicated at 18 for projecting flame and heated gases into an immersed melting member or flue system embodying the longitudinally extending flue member 20 which is located near the bottom of the receptacle and extends substantially from end to end with the burner end provided with an opening 21 juxtaposed to the outlet of burner 18.

At the far end, the flue divides into two arms 22 and 23 through a T-connection 24; and the said arms 22 and 23 extend parallel to the flue portion 20 to the burner end of the kettle where they are upwardly directed as chimneys 22' and 23', respectively, extending through the top for discharge of the spent gases. A pair of inclined stub or dead-end extensions 25 and 26 in the nature of short pipe lengths may be provided at the discharge end of the kettle, as is more particularly set forth in U. S. Letters Patent #2,175,886, granted to applicants' assignee the 10th day of October, 1939. These extensions are located upon opposite sides of a screen 30 for the molten material and surrounding the inner end 31 of a spigot 32 adapted for discharge of molten material from the receptacle.

Heretofore, such spigot and surrounding burner element have been fixedly secured to the receptacle wall; but in accordance with the present invention, both of these elements are mounted for ready removal from the interior of said receptacle at the same time that the interior of the said receptacle, particularly below the flue system, is rendered accessible for introduction of suitable cleaning implements externally manipulatable. Thus, there is provided in the end wall of the receptacle and substantially opposite the burner end of the flue system an opening 35 which, preferably, extends to the bottom of said receptacle, as indicated, and is of sufficient size to pass the discharge spigot with surrounding screen out of the kettle, as will hereinafter be more fully set forth. This opening is designed to be sealed, normally and while the kettle is in operation, by means of a clean-out door or sealing element 36 which may be hinged to or in any suitable manner attached to the wall of the receptacle, for example, as by means of suitable bolts 37 and nuts 38, with intermediate gasket 39.

This sealing element, furthermore, carries also the spigot, which passes therethrough as indicated in Figs. 1 and 5, as well as the strainer element surrounding the inner end of said spigot. Thereby, when the plate is removed, after unscrewing the nuts 38, both the spigot and strainer will be lifted out therewith from the interior of the receptacle, rendering the same free and unobstructed for introduction through the opening 35 of suitable implements which are manipulated externally of the receptacle to scrape and remove the deposited matter from the bottom of the kettle and the underside of the flue system. The upper portions of the flues are readily accessible from the top of the receptacle by raising or removing the covers 13, so that it becomes unnecessary in the present instance to resort to the bodily and troublesome removal of the flue system. By continuing opening 35 substantially to the bottom of the receptacle, any foreign material falling thereon is readily withdrawn over the edge of the opening with-

out causing any accumulation to remain thereon.

After the desired cleaning of the outer surface of the flue system has been effected, opening 35 is again sealed by restoring the clean-out element to its position thereover and locking the same through the bolts and nuts 37 and 38, as is well understood. This restores, also, the spigot to its proper location for discharge of a subsequent batch of molten material from the receptacle, in the usual manner.

Instead of the bolt and nut arrangement indicated for securing the clean-out element in position to seal the receptacle opening, an element 40, Fig. 6, may be locked in position over the opening 35 in receptacle 42 through a camming action effected by a pair of rockable levers 43 mounted on the kettle and having a cam surface 44 cooperating with a beveled surface 45 of a cooperating portion 46 of the element 40. A circumferential flange 47 extending beyond the rim bears through an intermediate annular gasket 48, when the levers 43 are correspondingly locked, upon the outer surface of the receptacle to insure an adequate seal of the opening while the kettle is in operation.

Or, a flange 50 through an intermediate annular gasket 51 may seal a clean-out element 52 to the outer surface of the wall of a receptacle 53 by means of a screw 54 whose inner end bears against a boss 55 of the head of a spigot 56. This screw is threaded through a yoke 57 removably held by its opposite arms 58 to a pair of respective hooks 59 as the screw is advanced 33 toward the end of the spigot.

Other means of effecting the sealing will, of course, suggest themselves, and we do not wish to be restricted to the specific expedients shown.

We claim:

1. In a melting kettle for tar, asphalt and the like comprising a melting receptacle provided with an opening at the top for receiving material to be melted, and a system of heating flues fixedly mounted within and extending longitudinally of the receptacle for immersion in the molten material therein and having a burner opening at one end: a removable element closing normally an opening in the receptacle wall substantially opposite the burner end of the heating flues, a spigot located below the bottom of the flues and carried by said element, said spigot having a closure element rotatable over its inner end of lesser radius than the smallest dimension of said receptacle opening and adapted for discharge of molten material from the receptacle, and means manually operable exteriorly of the receptacle for detaching the element with the spigot as a unit from the receptacle to admit of introducing cleaning implements beneath said flues for contact therewith.

2. In a melting kettle for tar, asphalt and the like comprising a melting receptacle provided with an opening at the top for receiving material to be melted, and a system of heating flues fixedly mounted within and extending longitudinally of the receptacle for immersion in the molten material therein and having a burner opening at one end: a removable element extending to the bottom of the receptacle and closing normally an opening in the receptacle wall substantially opposite the burner end of the heating flues, a spigot located below the bottom of the flues and carried by said element, said spigot having a closure element rotatable over its inner end of lesser radius than the smallest

dimension of said receptacle opening and adapted for discharge of molten material from the receptacle, and means manually operable exteriorly of the receptacle for detaching the element with the spigot as a unit from the receptacle to admit of introducing cleaning implements beneath said flues for contact therewith.

3. In a melting kettle for tar, asphalt and the like comprising a melting receptacle provided with an opening at the top for receiving material to be melted, and a system of heating flues fixedly mounted within and extending longitudinally of the receptacle for immersion in the molten material therein and having a burner opening at one end: a removable element closing 15 normally an opening in the receptacle wall sub-

stantially opposite the burner end of the heating flues, a spigot located below the bottom of the flues and carried by said element, said spigot having a closure element rotatable over its inner end and adapted for discharge of molten material from the receptacle, a strainer attached to the removable element, surrounding the inner end of the closure element and being smaller than the said receptacle opening, and means 10 manually operable exteriorly of the receptacle for detaching the element with the spigot and the strainer as a unit from the receptacle to admit of introducing cleaning implements beneath said flues for contact therewith.
